(57) **CLAIM**

The ornamental design for a module for filtration, as shown and described.

DESCRIPTION

FIG. 1 is a front perspective view of a module for filtration showing our new design;

FIG. 2 is a front view, the rear view being a mirror image of the front view;

FIG. 3 is a left side elevational view, the right side elevational view being a mirror image of the left side elevational view;

FIG. 4 is a top plan view;

FIG. 5 is a bottom plan view; and,

FIG. 6 is a perspective view of the module for filtration used in a filtration system.

The broken lines shown in FIG. 6 are for illustrative purpose only and form no part of the claimed design.
